UNITED STATES PATENT OFFICE.

SAMUEL F. MERRITT, OF SPRINGFIELD, MASSACHUSETTS.

IMPROVEMENT IN EYE-GLASS SUSPENDERS.

Specification forming part of Letters Patent No. 122,629, dated January 9, 1872.

SPECIFICATION.

I, SAMUEL F. MERRITT, of Springfield, Hampden county, Commonwealth of Massachusetts, have invented an Improvement in "Eye-Glass Suspenders," of which the following is a specification:

Nature and Objects.

My invention relates more particularly to an improvement upon my eye-glass holder patented October 16, 1866, No. 58,867, and consisting of a device to be hooked into the vest or other garment of the wearer for the purpose of retaining the glass securely, so as to be easily detached at pleasure, and so as to enable the troublesome cord, chain, or ribbon usually used to secure glasses to be entirely dispensed with. The ring of the handle of the glass being forced past the spring-hook rests in the loop of the holder, where it is free to move or oscillate; but as an unusually-strong jerk might detach the glass without the wearer's knowledge, and as it would be difficult to make a light thin metal suspender, the hook of which would have spring enough to resist the ring of the glass acting as a wedge between it and its bearing, I punch out and form from the metallic shank, (or back of the loop,) and opposite the hook, a tongue, which, being connected at its upper end to the stock, has its lower end turned away from, and its main length brought to bear against, the hook, so that while yielding to the passage of the glass between the hook and itself, it springs back against the hook and permits the ring of the glass following the back of the loop to come

against the angle of its departure from the shank and where the metal is solid, thus forming an effectual guard against any escape of the glass, while, by the slight turn given to its free end, the glass can be withdrawn between it and the hook, at will.

In the drawing, Figure I is a perspective view, and Fig. II a profile view of my invention.

General Description.

A is the bar, extending upon both sides of the suspender, at its top, for the purpose of holding it more steadily in position. D is the attachment-pin, hinged at *c* to the back of the bar, and having its point received within the catch *b*. L is the spring-hook, closed against the back or shank H of the suspender; and I is the spring-tongue or guard, bearing against the hook and retaining the glass so securely within the loop of the holder that the ring of the glass itself will break before it can escape; and by these means I am able to make a thin light metallic holder that shall have all required strength.

Now, having described my invention, what I claim as new, and desire to secure by Letters Patent, is—

In combination with the shank or back H, spring-hook L, bar A, and pin D, the spring-tongue or guard I, constructed and arranged substantially as hereinbefore specified.

SAMUEL F. MERRITT.
